(57) **CLAIM**

The ornamental design for a glove, as shown and described.

DESCRIPTION

FIG. 1 is a bottom view of a glove showing our new design;
FIG. 2 is a left side elevational view thereof;
FIG. 3 is a right side elevational view thereof; and,
FIG. 4 is a perspective bottom view thereof.

The portion of a glove shown in broken lines in the drawings
illustrates the article to which the design is applied, and forms
no part of the claim.

The stippling in the drawings represents texture.
